UNITED STATES PATENT OFFICE.

JOHN S. HOLLIDAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,324,152.

Specification of Letters Patent.

Patented Dec. 9, 1919.

Application filed December 15, 1917. Serial No. 207,252.

To all whom it may concern:

Be it known that I, JOHN S. HOLLIDAY, a citizen of the United States, residing at Wilkinsburg, in the county of Allegheny and State of Pennsylvania, have invented certain new and useful Improvements in Railway Signaling, of which the following is a specification.

My invention relates to railway signaling, and particularly to signaling of the type embodying alternating current track circuits and alternating current track relays. More specifically, my invention relates to systems of this character wherein the relay comprises two windings one of which receives energy from the track circuit and the other directly from the source independently of the track circuit.

One object of my invention is the provision, in systems of this character, of means for improving the phase relation between the currents in the two relay windings, and for at the same time reducing to the lowest possible degree the amount of current which must be supplied to the track winding of the relay through the track rails.

I will describe one form of signaling system embodying my invention, and will then point out the novel features thereof in claims.

In the accompanying drawings, Figure 1 is a diagrammatic view showing one form of signaling system embodying my invention. Fig. 2 is a vector diagram showing the conditions which would obtain in the system shown in Fig. 1 if the condenser C were omitted. Fig. 3 is a vector diagram showing the conditions which actually obtain in the system shown in Fig. 1 when the condenser is used. Fig. 4 is a view showing an electrical equivalent of the condenser and secondary winding on the relay R of Fig. 1.

Referring now to Fig. 1, the reference character T designates the track rails of a railway, which rails are divided by insulated joints 2 to form a track section or a block section C—D. This track section is provided with a track circuit comprising, as usual, the track rails of the section, a source of alternating signaling current for supplying energy to the rails adjacent one end of the section and a track relay having a winding receiving energy from the rails adjacent the other end of the section. The source of

signaling current, as here shown, is a generator G of alternating current which is connected with transmission mains P extending along the railway. Current from this source is supplied to the track rails adjacent one end of the section through the medium of a transformer A, whose primary is connected with said transmission mains P and whose secondary is connected with the track rails, a reactance 3 being inserted between one rail and the transformer secondary as shown.

The relay, which is designated R, comprises a vane 4 of electro-conductive non-magnetizable material, such as aluminum, fixed to a shaft 5 which is journaled so that the vane may move in air gaps 6^a and 7^a in two magnetizable cores 6 and 7. Core 7 is provided with a winding 9 which is connected with the track rails T, and so I will term this winding the "track winding" of the relay. Core 6 is provided with a winding 8, 8 which is connected with a secondary winding 14 of a transformer A', the primary of which is connected with the transmission mains P. Consequently, this winding 8, 8, which I will term the "line winding" of the relay, receives energy from the source G independently of the track rails or through the medium of means not including the track rails. The cores 6 and 7 are so located and disposed that the fluxes in the core 6 pass through the vane 4 substantially on opposite sides of the flux in core 7; that is, the air gap 7^a is substantially between the two gaps 6^a, 6^a. The principle of operation of a relay of this type is well understood by those versed in the art, hence for the purposes of this specification it is sufficient to say that when the windings 8 and 9 are supplied with alternating currents of the same frequency and of the proper relative phases a torque is exerted on the vane tending to swing it in counter-clockwise direction to the position in which it is shown in the drawing. When winding 9 is deenergized, however, the torque disappears and the vane swings downwardly in clockwise direction due to the force of gravity. The shaft 5 on which the vane is mounted controls a contact 12 in such manner that this contact is closed when both windings of the relay are properly energized, but is opened when the vane swings downwardly due to deenergiza-

tion of the track winding 9. It is understood that a car or train in track section C—D shunts all or nearly all of the current from winding 9 so that this winding then 5 becomes deenergized.

The core 7 is provided with a secondary winding 10 to which a condenser 11 is connected. The function of this condenser will be explained hereinafter.

10 The track section C—D is provided with a signal S for governing traffic therethrough, which signal is controlled by contact 12 of relay R in the usual and well-known manner. The supply of current for this signal is obtained from a secondary winding 13 on transformer A'.

When the propulsion energy for the railway is electricity and both track rails are included in the circuit for the propulsion 20 current, means must be provided for conducting such current around the insulated joints 2. As here shown, this is accomplished by the usual inductive bonds, each comprising a magnetizable core 17, and a 25 winding thereon the terminals of which are connected with the two track rails; each winding has a tap at its middle point which is connected by a conductor 16 with the corresponding tap on the adjacent bond of 30 the adjacent track section. As is well understood, these bonds conduct the propulsion current freely from section to section, but maintain the desired difference of potential of the signaling current across the 35 rails of each section.

As is well understood, a relay R of the type herein shown operates most efficiently when the currents in the two windings 8 and 9 differ by 90° in phase, and will not operate at all when these currents are of the same 40 phase. Owing, however, to the low power factors of these windings (about 0.3 for each), it is impossible to secure much phase displacement, even with the use of the 45 reactance 3. The function of the condenser 11 is to enable a considerable phase displacement to be secured. In order to explain how the condenser accomplishes this result, I will first show the conditions which would 50 obtain without the condenser, and then the conditions which obtain when the condenser is employed.

Referring now to Fig. 2, which shows the conditions without the condenser, the line 55 O—E represents the voltage applied to the track winding 9 of the relay, and the line O—I^o represents the position of the current in this same winding. This current lags behind the applied voltage by a wide angle, 60 because the power factor of the winding is very low—about 0.3. Assuming now that the power factor of the reactance 3 is 0.1, which is about as low as can be obtained, the voltage drop across this reactance is at 0.1 65 power factor to the current O—I^o, and so

may be represented by the line E—X. The total voltage drop across the reactance 3 and the relay winding 9 is, then, represented by line O—X. It is apparent at once that the current O—I^o does not lag much farther 70 behind O—X than it does behind O—E. Now, the voltage applied to the line winding 8 of the relay is nearly in phase with the line O—X, and since the power factor of this winding is also about 0.3, the current in the line winding will be in about the 75 position indicated by line O—I^s. It is obvious, then, that the currents in the two windings 8 and 9 are nearly in phase, so that these windings cause very little torque to be 80 exerted on the vane 4.

This difficulty is avoided by the use of the condenser 11, and the conditions which obtain are illustrated by the vector diagram Fig. 3. Before explaining this diagram, it should be pointed out that in making a vector diagram for apparatus involving a transformer, the current in the secondary may be considered to be flowing in a path connected in multiple with the primary. 90 Bearing this in mind, the arrangement of the primary 9, secondary 10 and condenser 11, shown in Fig. 1, is electrically equivalent to the arrangement shown in Fig. 4 where the condenser 11^a is connected directly in 95 multiple with winding 8. The chief reason for using the transformer arrangement shown in Fig. 1 is to step up the voltage applied to the condenser and so enable a smaller condenser to be used than would be 100 the case were this condenser connected directly across the winding 9. By placing the secondary 10 directly on the relay core 7, I avoid the cost of a separate transformer and also the losses due to the exciting current 105 for a separate transformer.

Referring now to Fig. 3, the line O—E represents the voltage applied to the track winding 9, and the line O—I^o the current in this winding, exactly as in Fig. 2. The current taken by the condenser in Fig. 4 is nearly in leading quadrature to the voltage O—E, and so is represented by line O—C. The current in the track circuit is the vector sum of O—I^o and O—C, and may be made 115 of substantially unity power factor so that it may be represented by line O—S, that is, in phase with O—E. Although the current in the track circuit is in the position O—S, it must be borne in mind that the magnetic 120 flux in the core 7 is substantially in phase with the current O—I^o in winding 9, and that it is the phase relation between the fluxes in cores 6 and 7 which determines the torque on the vane 4. The voltage drop 125 across the reactance 3 is at approximately 0.1 power factor with respect to current O—S, and so may be represented by line E—X. The voltage at the secondary of transformer A is, then represented by line 130

O—X. Since the voltage applied to the line winding 8 is substantially in phase with the voltage at the secondary of transformer A, it follows that this voltage on the line 5 winding is likewise represented by line O—X. The power factor of this winding being 0.3, the current therein is represented by the line O—I⁸, which line also represents the magnetic flux in core 6. The phase 10 placement between the fluxes in the two cores is then represented by angle I⁹—O—I⁸, hence considerable torque will be exerted on the vane 4. The efficiency of the relay is, consequently, good.

15 It is a wellknown fact that the transmission of current through track circuits is very uneconomical, and it is very desirable, therefore, to reduce the amount of current which must be applied to the track winding of a 20 relay to the lowest possible value. By referring to Fig. 2 it is evident that when the condenser 11 is not used, the current which must be transmitted through the rails is considerable, the value being represented by 25 the line O—I⁹; but by referring to Fig. 3 it will be seen that when the condenser is used the current which must be transmitted through the track rails is O—S, which may be made less than one-half of the current 30 O—I⁹. The use of the condenser, therefore, materially reduces the volt-amperes which must be transmitted through the track rails.

So far as the track winding 9 alone of the 35 relay is concerned, what the condenser actually does is to supply the wattless component of the current taken by this winding. That is, the condenser is of such size that the circuit of the secondary 10 is resonant to current of the signaling frequency.

40 When the relay is used on an electric railway employing bonds in the trackway as shown in Fig. 1, the condenser 11 may be made larger than is necessary to supply the wattless component of the current for track 45 winding 9, and the extra current taken by the condenser may be made to neutralize the wattless component of the current for the bond at the relay end of the track section.

Although I have shown and described 50 only one form of signaling system embodying my invention, it is understood that various changes and modifications may be made therein within the scope of the appended claims without departing from the 55 spirit and scope of my invention.

Having thus described my invention, what I claim is:

1. A railway signaling system comprising, in combination with the rails of a track 60 section, a source of alternating signaling current connected with said rails, a relay having two magnetizable cores, a winding on one core receiving energy from said track rails, a winding on the other core 65 receiving energy from said source but not

through said rails, a secondary winding on said first-mentioned core, and a condenser connected with said secondary winding.

2. A railway signaling system comprising, in combination with the rails of a track section, a source of alternating signaling current connected with said rails, a relay having a track winding which receives energy from said track rails and a line winding which receives energy from said source 70 but not through said rails, and means associated with the said track winding for increasing the power-factor of the current which flows therein.

3. A railway signaling system comprising, in combination with the rails of a track section, a source of alternating signaling current connected with said rails, a relay having a track winding which receives energy from said track rails and a line winding which receives energy from said source but not through said rails, and a condenser associated with said track winding for supplying the wattless component of the current taken by said winding.

4. A railway signaling system comprising, in combination with the rails of a track section, a source of alternating signaling current connected with said rails, a relay having a track winding which receives energy from said track rails and a line winding which receives energy from said source but not through said rails, and means associated with said track winding which takes a wattless current leading the voltage applied to 100 said winding.

5. A railway signaling system comprising, in combination with the track rails of a track section, a source of alternating signaling current, a transformer whose primary is connected with said source and whose secondary is connected with said rails, a reactance included in the connection between one of the rails and the transformer secondary, a relay having a track winding 105 receiving energy from said rails and a line winding receiving energy from said source but not through said rails, and a condenser associated with said track winding and taking a wattless current leading the 110 voltage applied to said track winding.

6. A railway signaling system comprising, in combination with the track rails of a track section, a source of alternating signaling current, a transformer whose primary is connected with said source and whose secondary is connected with said rails, a reactance included in the connection between one of the rails and the transformer 125 secondary, a relay having a track winding receiving energy from said rails and a line winding receiving energy from said source but not through said rails, and a condenser associated with said track winding for causing the current in the track rails to 130

be substantially in phase with the voltage across said track winding.

7. A railway signaling system comprising, in combination with the track rails of a track section, a source of alternating signaling current, a transformer whose primary is connected with said source and whose secondary is connected with said rails, a reactance included in the connection between one of the rails and the transformer secondary for causing the current in the rails to lag behind the voltage across said secondary, a relay having a track winding receiving energy from said rails and a line winding receiving energy from said source but not through said rails, the power factors of said windings being low, and a condenser associated with said track winding for causing the current in the track rails to be substantially in phase with the voltage across said rails, whereby the fluxes pro-

duced by the currents in said two relay windings are displaced by a considerable angle.

8. A railway signaling system comprising, in combination with the rails of a track section, a source of alternating signaling current connected with said rails, a relay having a track winding which receives energy from said track rails and a line winding which receives energy from said source but not through said rails, and means associated with one of said windings which takes a wattless current leading the voltage applied to such winding. 25 30 35

In testimony whereof I affix my signature in presence of two witnesses.
